UNITED STATES PATENT OFFICE.

WILLIAM HENRY BOVARD, OF LOS ANGELES, CALIFORNIA, ASSIGNOR OF ONE-THIRD
TO GEORGE O. MOORE, OF LOS ANGELES, CALIFORNIA.

ADJUSTABLE JOINT.

Application filed September 18, 1922. Serial No. 596,296.

To all whom it may concern:

Be it known that I, WILLIAM HENRY BOVARD, a citizen of the United States, and a resident of Los Angeles, county of Los Angeles, and State of California, have invented a new and useful Adjustable Joint, of which the following is a specification.

The present invention relates to improvements in adjustable joints and has particular reference to a joint to be used for securing the bumper of a motor vehicle to the frame of the same. It constitutes an improvement on a similar device described by me in my co-pending application, Serial No. 565584, the improvement consisting in a more perfect locking engagement between the members to be joined.

The frame of a motor vehicle usually curves downward where it engages the vehicle spring, and these curves vary with the different makes of motor vehicles. The frames also vary in cross section and it is one of the objects of the present invention to provide a suitable joint between the bracket holding the bumper and the frame member that may be used for practically any motor vehicle and may be easily adjusted so as to maintain the bumper in its proper position.

With these objects in view I have shown the preferred form of my invention in the accompanying drawing in which Figure 1 shows a side elevation of my device secured to the frame of an automobile, Figure 2 a top plan view of the same, Figure 3 a vertical longitudinal section through my joint, Figure 4 a cross section through the same along line 4-4 of Figure 3, Figure 5 a side elevation of a casting forming one of the members of my joint, Figure 6 a top plan view of the casting and Figure 7 a top plan view of the assembled joint, a portion being shown in section to disclose the shape of the engaging surfaces. While I have shown only the preferred form of the invention I wish to have it understood that various changes may be made within the scope of the claims hereto attached without departing from the spirit of the invention.

The frame member (1) of a motor vehicle terminates in a curved end (2) engaging the main spring (3). To this curved end is secured by means of a suitable clamp (4) the casting (6) the end surface (7) of which is slightly curved so as to rest snugly on the

curved surface of the frame. The casting is provided with two lateral projections (8) and (9), each of which is perforated as shown at (10) and (11) and the clamp (4) passes through these two perforations to be secured by any suitable means as by the nuts (12). The perforation (11) is elongated as shown in Figure 6, which adapts the casting to be used for frames of different widths. From the casting extends rearwardly an arm (13) preferably cylindrical in shape as shown in Figure 5. This arm is disposed in spaced relation and parallel to the vertical central plane of the casting and has a toothed or corrugated internal surface (14), the teeth or corrugations being arranged radially. The body portion of the casting presents a curved rear surface (16) adapted to receive a cylindrical holding element (17) for the bracket (18).

The latter bracket is shown in Figure 1 as being substantially triangular in shape, its base (19) having the bumper rod (21) secured thereto by means of a clamp (22), and its two sides (23) and (24) instead of joining at the apex of the triangle terminating in parallel lips (26) adapted to be inserted into the cylindrical element (17) through longitudinal slots (27) in its curved surface. The cylindrical element (17) is hollow, but the side opposing the two slots (27) is made solid by the segment (28) which provides a stop for the lips (26). One end of the cylinder is solid as shown at (29) and its surface is provided with radial teeth or corrugations registering with the corrugations (14) of the casting and adapted to engage the same. At the opposite end of the holding element I provide a washer (31) and all the elements, namely, the arm of the casting, the solid end of the holding element (17), the lips of the bracket and the washer are firmly held together by means of a bolt (32) penetrating registering perforations in the said elements and the nut (33) threadedly engaging the end of the same.

To assemble the device the casting (6) is placed on the curved surface of the frame member and firmly secured thereto by means of a clamp (4) and the nuts (12). The lips of the bracket may then be inserted into the cylindrical holding element (17) in the manner described, the solid end of the cylinder engaged with the corrugated surface of

arm (6) of the casting, the washer inserted and all the elements combined into one solid unit by means of the bolt (32) and the nut (33). It will be seen that due to this construction the base of the triangular bracket may always be maintained in a vertical position irrespective of the shape of the frame and the position of the bracket may be adjusted at any time by merely loosening the nut (33) of the bolt (32). The casting is adapted to fit on any frame member within reasonable limits due to the elongated perforation (11) and the cylinder can hold any size of brackets. If for instance brackets narrower than the length of the slots were selected it would only be necessary to tighten the nut on the bolt (32) so as to force the washer (31) into firm contact with the lips.

20 The device is superior to that described in my copending application, previously referred to, in its simplicity and furthermore by the fact that it allows of a more ready engagement between the corrugated surfaces.

I claim:

1. An adjustable joint of the character described, comprising a casting terminating in a flat arm, a cylinder having one solid end adapted to engage the flat arm and to support a bracket in its central portion and means for securing the cylinder to the arm.

2. An adjustable joint of the character described, comprising a casting terminating in a flat arm, a cylinder having one solid 35 end adapted to engage the flat arm and to support a bracket in its central portion, a washer at the other end adapted to bear on the bracket so as to hold the same, and a central bolt extending through the arm 40 and the cylinder for binding all the elements into one firm unit.

3. An adjustable joint of the character described, comprising a casting terminating in a flat arm presenting a circular surface 45 with radial corrugations therein, a cylinder having one solid end with registering corrugations adapted to engage said surface and to support a bracket in its central portion and means for securing the cylinder 50 to the arm.

4. An adjustable joint of the character described, comprising a casting terminating in a flat arm presenting a circular surface with radial corrugations therein, a cylinder 55 having one solid end with registering corrugations adapted to engage said surface and to support a bracket in its central portion, a washer at the other end adapted to bear on the bracket so as to hold the same, 60 and a central bolt extending through the arm and the cylinder for binding all the elements into one firm unit.

WILLIAM HENRY BOVARD.
